UNITED STATES PATENT OFFICE.

HERBERT G. MACKINNEY, OF PROVIDENCE, RHODE ISLAND.

DESIGN FOR EAR-RINGS AND OTHER JEWELRY.

SPECIFICATION forming part of Design No. 12,266, dated May 17, 1881.

Application filed January 25, 1881. Term of patent 14 years.

To all whom it may concern:

Be it known that I, HERBERT J. MACKINNEY, of the city and county of Providence, and State of Rhode Island, have invented and produced 5 a new and original Design for Ear-Drops and other Articles of Jewelry, of which the following is a specification, reference being had to the accompanying drawing, forming a part thereof.

10 The said design is represented in the accompanying drawing; and it consists of a ring, *g*, having rings or leaves *w*, substantially as shown, extending radially from the under or reverse side of the ring, and attached thereto, 15 forming an ornamental border around the ring. Above the ring *g* is mounted a flat bar, *b*, with two balls, *a a*, attached to the under side thereof, and the fan-shaped ornament *f*, sur- 20 mounting said bar, as shown. The outer edge of said ornament *f* may be indented or scalloped, and the surfaces of the wings *w* and of the balls *a*, and likewise the other parts of said 25 design, may be engraved, enameled, or otherwise ornamented, and within the ring *g* may be placed any suitable pendant or setting.

Said ring, with its radial ornaments, as rep-

resented, may be used separately for an ear-drop, pin, or other article of jewelry, and a similar use may be made of the bar *b*, with its ornamented parts *a a* and *f*. 30

What I claim, and desire to secure by Letters Patent, is—

1. The design for an ear-ring, pin, or other article of jewelry to which it may be appropriate, herein shown and described, the same 35 consisting of the ring *g*, the radial ornaments or wings *w*, the bar *b*, balls *a a*, and fan-shaped piece *f*.

2. The design for an ear-ring, pin, or other appropriate article of jewelry, consisting of 40 the ring *g*, with the radial wings *w*, substantially as described, and shown in the accompanying illustration.

3. The design for an ear-ring, pin, or other article of jewelry, consisting of the bar *b*, balls 45 *a a*, and fan-shaped ornament *f*, herein shown and described.

HERBERT G. MACKINNEY.
